UNITED STATES PATENT OFFICE.

MATHEAS PALUSKA, OF ROANOKE, ILLINOIS, ASSIGNOR, BY MESNE ASSIGNMENTS, TO GETZ POWER WASHER CO., OF MORTON, ILLINOIS, A CORPORATION OF ILLINOIS.

WRINGER.

1,158,148.

Specification of Letters Patent. Patented Oct. 26, 1915.

Application filed November 23, 1912. Serial No. 733,145.

To all whom it may concern:

Be it known that I, MATHEAS PALUSKA, a citizen of the United States, residing at Roanoke, in the county of Woodford and 5 State of Illinois, have invented new and useful Improvements in Wringers, of which the following is a specification.

This invention relates to clothes wringer operating and supporting means, and has 10 for an object to provide means whereby the wringer may be supported by a vertical driving shaft without a special separate support.

It is a further object to provide an operative connection and journal bracket between 15 the vertical shaft and a horizontal shaft whereby the wringer may be carried upon the horizontal shaft and be movable to any desired position around the vertical shaft.

It is also a purpose to make the device 20 available at a low cost.

Other objects and advantages may be apparent in addition to those mentioned.

In the drawings, Figure 1 is a side view of the device, Fig. 2 is a top view thereof, adjacent a washing machine, the operative and 25 inoperative positions being indicated.

There is illustrated a washing machine 10 of any suitable construction, including a tub element 11. Extending vertically and adjacent the tub there is a driving shaft 12 which may be operated by the mechanism of 30 the washing machine if desired. It carries near its upper end a bracket 14 revolutely mounted thereon, and including the lower 35 sleeve 13 engaged snugly around the shaft and supported by the collar 15 secured to the shaft therebeneath. A suitable oil cup 13' is carried by the sleeve for lubrication of the shaft journaled therein. An upwardly 40 curved bracket arm 16 projects from the sleeve, its upper end being spaced some distance above the upper end of the shaft, and having a journal bearing sleeve 17 thereat disposed on an axle at right angles to the 45 shaft 12. A wringer shaft 18 is revoluble therein, held against longitudinal movement by two sleeves 18' on each side of the bearing. This shaft carries at its end inwardly of the arm 16 a beveled gear 19 50 meshed with a similar one 20 carried by the upper end of the shaft 12. A suitable housing 21 may be engaged over these gears and supported by the bracket arm whereby accident is due to clothing or parts of the person

becoming caught in the gears may be averted. The sleeve 17 is provided with an oil cup 17'.

The shaft 18 projects some distance outwardly of the bearing 17, and is revolubly mounted in the standards 22 of a wringer device. Between the standards the shaft carries a suitable roller 23 of rubber or other suitable material, superposed over which there is a similar roller 24, having a central shaft element 25 projecting from each end of the roller and engaged slidably in slotted portions of the standards. Blocks 26 are engaged over the shaft ends, borne downwardly by springs 27 thereabove, the tension of the springs being adjustable by means of hand screws 28 projecting above the standards, this construction being similar to that ordinarily employed in wringers. The shafts 18 and 25 both project outwardly of the outermost standard and carry intermeshed gears 29. The standards are connected by the cross beam, B. The bracket 14 includes a lower brace arm 30 extending horizontally to a point near the outer part of the wringer and in the major plane thereof its outer end portion being inclined upwardly and secured to the outermost standard, whereby the wringer is retained securely in an upright position, and the device firmly braced against depression.

It will be noted that the tendency of the driving shaft to rotate the device bears it in a direction opposite that in which fabrics move in passing through the wringer, so that when adjacent the tub 10 for use the device will be held in position. When moved to inoperative position it may be held by any suitable means, such as a securing rod 31, or other suitable means. As the weight of fabrics sustained by the wringer while passing therethrough is inconsiderable,—the major portions of such fabrics being carried by the receptacles from which they are taken and into which they are discharged,—no undue strain will be set up in the shaft 12, and the operation of the device will not involve excessive friction.

What is claimed is:

In a wringer, the combination of a vertically disposed driving shaft; a bracket revolubly carried on the upper end of said shaft, said bracket including a sleeve, a curved bracket arm having a journal bear-

ing sleeve disposed in a horizontal plane and a lower brace arm; a wringer, including a pair of shafts and rollers thereon, one of said wringer shafts being extended and having a bearing in said journal bearing sleeve of said curved bracket arm; said wringer being supported at its outer end by said brace arm; gearing between said driving shaft and said extended wringer shaft; a housing for

said gearing, and a securing rod for holding 10 said wringer in a certain position.

In testimony whereof I have hereunto set my hand in presence of two subscribing witnesses.

MATHEAS PALUSKA.
